Primary Examiner—Ian Simmons(74) *Attorney, Agent, or Firm*—Oblon, Spivak, McClelland, Maier & Neustadt, P.C.(57) **CLAIM**

The ornamental design for an assay card for an assay chamber, as shown and described.

DESCRIPTION

FIG. 1 is a top plan view of an assay card for an assay chamber, showing my design;

FIG. 2 is a bottom plan view thereof; and,

FIG. 3 is a top, front and right side perspective view thereof. The broken line showing in the figures is for illustrative purposes only and forms no part of the claimed design.
